UNITED STATES PATENT OFFICE.

WILLIAM H. SHAFER, OF SACRAMENTO, CALIFORNIA.

AUTOMATIC ELEVATOR GATE.

Application filed June 30, 1924. Serial No. 723,317.

To all whom it may concern:

Be it known that I, WILLIAM H. SHAFER, a subject of the King of England, and a resident of Sacramento, county of Sacramento, State of California, have invented a new and useful Automatic Elevator Gate, of which the following is a specification.

This invention relates to elevator gates of the sliding variety as principally used on freight elevators.

The objects of my invention are to provide simple apparatus actuated by the elevator in ascending or descending whereby the gate or gates at each floor are successively opened and closed as the elevator approaches or leaves the particular floors, also means controlled by the elevator operator for rendering the gate opening apparatus inactive in passing any floor or floors, also such apparatus which can be furnished as a complete unit applicable to any ordinary freight elevator and easily connected to the existing sliding gate, and also such apparatus as will not only open the gate but also permit it to close gently upon motion of the elevator.

I achieve the objects outlined by the apparatus shown in the accompanying drawings and in which:

Figure 1 is an elevation of the gate lifting and closing apparatus showing the sliding blocks and connection to gate. Figure 2 is a side view of Figure 1 with portions broken out to show the spring block latch.

Figure 3 shows a compound pulley and rope arrangement for lifting the gate a greater distance than the sliding movement of the block latch to reducing the length of the apparatus for a given movement of gate.

Figure 4 shows in sectional elevation the elevator floor with tripping control lever for rendering the lifting apparatus inoperative at any desired floor.

Figure 5 is an enlarged sketch of the engaging plate. Figure 6 is a similar sketch of the pin plate upon which the engaging plate slides, and Figure 7 is a reduced plan view of the elevator floor indicating the relative positions of the various elements mentioned.

In detail my apparatus consists of a double track or guide unit (1) to be secured vertically at the side of the elevator shaft adjacent the sliding door (2) to be opened, preferably two for each door, one to

either side of the elevator so the door will be raised evenly by a rope (3) at opposite points, though if the gate is narrow or has long guides, one hitch will suffice, or if desired a double rope may be used and guided over any desired arrangement of pulleys to opposite points on the door.

The rope passes upward over a fixed pulley (9) and the end of the rope is secured to a sliding block (4) sliding vertically between the track members (5) and (6) and retained therein by overlapping edges as indicated.

From the lower end of the block is a rope or chain (7) extending downwardly and around a pulley (8), thence upwardly and connected to a similar sliding block (4'), slideable between members (5') and (6').

The sliding gate thus hangs upon the rope (3) pulling the block (4) upward and the latter through its rope (7) pulls the block (4') downward.

To resist this downward pull on block (4') and keep the rope (7) taut so that the sliding blocks will be properly spaced, means is provided to yieldingly pull the block (4') upward. This means can assume a variety of forms, it may be a long spiral spring (10) secured to the block at (11) and to the guide unit at (12), the desired function being to keep the blocks spaced and tied together so that as one is moved along the guide in one direction, the other will move in opposite direction. Since the gate hangs on the rope (3) connected to block (4) it is manifest that in the position shown in Figure 1 that the sliding of either block toward the center of the guides will raise the gate.

To move either block thus toward the center, means is provided on the elevator to engage one block in ascending and the other in descending of the elevator, and a spring latch (18) and (18') is provided respectively on the blocks so that the engaging means on the elevator will only push the block in one direction, i. e. toward the center of the guide, and may be released or tripped from engagement with the elevator at a certain point of travel.

This latch can assume many forms but is here shown as pivoted to the block at (19) and working freely in a depression in the block whereby it may swing down at an angle as shown at (20) in Figure 2 or to the position (21) perpendicular to the block. A spring (22) which has one end inserted in a

groove of the block is provided to normally hold the block perpendicular projecting above the tracks.

In Figure 2 it will be observed that the guides or tracks for the blocks are both slanted at their central portions X away from the vertical line (23), and this is for the purpose of trapping the blocks under the latch engaging means carried by the elevator and which consists of a steel plate (24) slideable to and from the elevator (32) on guiding pins (25) carried by a pin plate (26) secured to the side edge of the elevator, or one to each side where double units are used 15 for each gate.

These plates are arranged to lie against the outer surface of the guide members (5) and (6), (5') and (6') to engage the latches of the blocks during the travel of the elevator but may be pulled back on their respective pin plates and out of engagement with the guides by means of a hand lever (27) connected to suitable linkage (28) whereby rods (29) secured to the plates will 25 slide the plates on the pins.

The rods (29) are suitably guided for sliding action in bearings (30) and also have a branch or brace (31) extending and secured to the plate to prevent it from tipping.

30 In operation, assuming the elevator to be at a higher story and descending, the plate will engage latch (18) and pull it downward with its block (4), thereby raising the gate (2) by the rope (3). When the plate descends to the position as dotted at (24) on Figure 1, the block will have started over the slanted part of the track thereby drawing the latch away from engagement with the plate. In the figure the latch (18) as 35 dotted at A is supposed to be withdrawn so that the plate is about to ride over it upon further downward movement.

In the meantime, the other block (4') has been pulled upward by the spring mentioned, its latch has contacted the plate and swung back and passed under the plate as indicated at B.

When once under the plate the latch (as at B) is trapped, for the block cannot then 50 be withdrawn as the latch will try to assume a perpendicular position through means of its spring and thereby wedge itself under the plate in any attempt to slide the block backwards over the slanted portion of the track.

Then upon continued descent of the elevator the plate passes over the latch A as well as B, but by reason of the notch or cut out corner (33') of the plate, the latch B 55 is released just before the latch A with the result that the latch B rises in its block and engages the notched edge of the plate and permits the block (4') to descend with the elevator, and consequently the gate until the latter is closed.

Upon upward movement of the elevator the operation is just the same except that block (4') is first lifted (also the gate), the blocks are trapped, and block (4) is first released over the lower notched corner (33).

It will thus be seen that the gate opens and closes at elevator speed in either direction and if the weight of the gate is not sufficient to make it act promptly a spring or additional weight may be used to assist it. 70 Also, if it is desired to open and close with a lesser movement of the elevator the gate rope (3) may be secured to a compounding block (34) receiving several turns of rope (3') from the gate (2') after first passing 80 around a fixed pulley block (35); thus any relation of travel of gate to elevator is possible.

When an elevator is being used for through service the operator may use the 85 hand lever (27) to pull the plates away from the guides so that they will not engage the latches and push the lever back again just before reaching the floor where it is desired the gate should again operate. 90

If it should be desired to stop the operation of a gate at any particular floor for a considerable time, this may be best accomplished by simply unhooking the rope from the gate at (36) and placing on the hook 95 a weight lighter than weight (15) so that both blocks will be drawn by the heavier weight into the depressed or slanted portions X of the track guides, thus being permanent- 100 ly inoperative.

In installing my apparatus it is arranged so that the blocks (4) and (4') are trapped at the time the elevator is at the floor level and thus with gate fully opened.

I claim:

1. In an elevator, a vertically slideable gate, a vertically slideable block guided on a track arranged adjacent the elevator shaft, a flexible element extending from the block over a pulley to the gate whereby the gate is lifted upon sliding the block, and a movable device carried by the elevator adapted for engagement of the block upon travel of the elevator and for movement out of engaging position for free passage over the block, said 110 movable device comprising a plate supported and guided for movement in and out from the elevator, linkage secured to the plate for movement thereof and an operating lever connected to the linkage. 115

2. In an elevator, a slideable gate, a slideable block guided on a track arranged adjacent the elevator shaft, a flexible element extending from the block over a pulley to the gate whereby the gate is lifted upon sliding the block, and a movable device carried by the elevator adapted for engagement of the block upon travel of the elevator and for movement out of engaging position for free passage over the block, said movable 120 device comprising a plate supported and guided for movement in and out from the elevator, linkage secured to the plate for movement thereof and an operating lever connected to the linkage. 125

130

device comprising a plate supported and guided for movement in and out from the elevator, linkage secured to the plate for movement thereof and an operating lever connected to the linkage.

3. In an elevator, a slidable gate, a slid-
able block guided on a track arranged adja-
cent the elevator shaft, an element extending
from the block to the gate whereby the gate
is lifted upon sliding the block, and a mov-

able device carried by the elevator adapted
for engagement of the block upon travel of
the elevator and for movement out of engag-
ing position for free passage over the block,
said movable device comprising a plate sup-
ported and guided for movement in and out
from the elevator, linkage secured to the
plate for movement thereof and an operat-
ing lever connected to the linkage. 15

WILLIAM H. SHAFFER.
